ROLLER TOY

James L. La Forge, Caruthersville, Mo.

Application December 13, 1946, Serial No. 716,084

4 Claims. (Cl. 46—45)

1

This invention relates to a roller toy comprising a drum within which is mounted a magnet which may be placed under the tension of a spring in the nature of a twisted rubber band so that, upon untwisting of the said band, the drum will be given rotary motion about its axis and thus cause the drum to be propelled over a surface such as a floor, and the invention further comprises a truck or roller carriage having metallic magnetically attracted rollers or balls and having traction with the outer surface of said drum and maintained in such surface contact by virtue of the magnetic field produced by the poles of said magnet, said truck provided with means for supporting a figured member or other object.

With these and other objects in view the invention resides in the novel details of construction and combinations of parts as will be disclosed more fully hereinafter and particularly covered by the claims.

Referring to the accompanying drawings forming a part of this specification and in which like numerals designate like parts in all the views—

Fig. 1 is a vertical sectional view through a toy made in accordance with this invention;

Fig. 2 is a transverse sectional view taken as on the line 2—2 of Fig. 1 and looking in the direction of the arrows;

Fig. 3 is an enlarged sectional view of a modification of construction of the truck shown in Figs. 1 and 2.

The drum comprises a circularly formed wall 2 which may be cylindrical, conical, or of other shape, with drum heads generally identified by the numerals 3 and 4. The circularly formed wall 2 is to be of non-magnetic material and relatively thin so that magnetic lines of force may be effective therethrough, and similarly the drum heads may be and preferably are made of non-magnetic material. The drum head 3 comprises a wheel or circular disk 5 and a bowed plate 6 disposed exteriorly of the drum to provide the space 7 between said disk and said plate. The other drum head 4 also comprises a wheel or disk 8 and a bowed plate 9 associated therewith to provide the space 10 therebetween, the diameter of the circular disk 8 being the same as or different from the diameter of the disk 5 according to whether the toy is to roll on the floor in a straight line or in a curved path.

A bolt 15 is disposed centrally through the drum head 3 with a nut 16 positioned to contact the innermost face of the drum head, and a second nut 17 disposed to contact the outer face of the drum head, the spacing of the disk and plate of the drum head thus making possible a more or less rigid bearing for said bolt. The innermost end of said bolt is formed as a hook 18 to receive one end of a looped rubber band 19, and the shank 20 of said bolt is passed with a

2

loose fit through the branch 21 of a more or less U-shaped magnet generally identified by the numeral 22.

Another bolt 25 is disposed centrally through the other drum head 4 with a fixed collar 26 positioned to contact the innermost face of the drum head, and a nut 27 disposed to contact the outer face of said drum head, the spacing of the disk and plate of the drum head thus making possible a more or less rigid bearing for said bolt. The innermost end of said bolt 28 is passed with a loose fit through the opposite branch 29 of the U-shaped magnet 22, and said magnet branch is provided with a hook 30 to receive the other end of the looped rubber band 19.

The bottom portion or base 31 of the magnet is thickened and made materially heavy so that, when the drum is firmly held in the hand and said hand moved rapidly in a circular path, the magnet will be given a spinning movement within the drum about the axes of the bolts 15 and 25 to cause the rubber band 19 to become twisted and thereby receive considerable tension. When sufficient tension and/or twist has been thus imparted, the drum is quickly deposited on the floor and the hand removed therefrom, whereupon the twisted band will then be free to untwist, and in such untwisting impart rotary travel to the drum on the floor, the heavy base 31 maintaining said magnet in an upright non-rotative position all as will be readily understood. The upper extremities of the magnet branches 21 and 29 are inwardly directed as indicated at 32 and 33 to assume positions within the drum closely contiguous to the inner surface of the circular wall 2 of said drum, and spaced from each other a sufficient distance to generate a field of magnetic force therebetween.

The truck as illustrated in Figs. 1 and 2 comprises a platform 35 having two of its opposite sides directed downwardly as indicated at 36 to provide bearings for the axles 37 of a plurality of rollers 38, which rollers are adapted to contact and make traction with the outer surface of the wall 2 of the drum. To said platform there is secured the base of an upstanding pin 39 whose upper extremity is sharpened as indicated at 40. Preferably, all the parts of this truck are of non-magnetic material or rather material which is not subject to the influence of the magnetic field of the magnet 22, except that the balls or rollers 38 must be of some magnetically attracted material so that said truck will remain on the outer surface of said drum during the rolling of the toy on the floor, with said truck positioned on said surface as shown in Figs. 1 and 2 always above the opposed ends 32 and 33 of said magnet, for otherwise the truck would roll off the drum onto the floor. Any suitable figured member or other object may be carried by said truck as for ex-

ample a doll whose skeleton or frame is generally identified by the numeral 41, by the expedient of pushing the sharpened end 48 of the truck pin into a more or less solid portion of said doll or other object, wherefore it will be evident that the doll or object may be given various positions relative the truck in accordance with the direction of penetration of said pin therewith.

The truck may be otherwise formed from that shown in Figs. 1 and 2, one such modification being illustrated in Fig. 3 wherein the platform 35 has substituted therefor a more or less hollow base 45 the lower floor of which is provided with a plurality of circular openings such as 46, each opening being of a diameter slightly less than the diameter of a magnetically attracted metal ball such as 47 which is sprung or forced through the opening into the hollow interior of the base so as to be retained in said base with a portion of the ball exposed through said opening, as shown, for contact with the outer surface of the circular wall 2 of the drum. The material of said base may be as desired so long as it will permit the placement of the balls 47 in their respective openings or sockets.

It is obvious that those skilled in the art may vary the details of construction and arrangements of parts without departing from the spirit of this invention, wherefore it is desired not to be limited to the exact foregoing disclosure except as will be required by the claims.

What is claimed is:

1. A roller toy comprising a drum, and a truck; said drum comprising a circularly formed wall of non-magnetic material, oppositely disposed heads, a substantially U-shaped magnet rotatably supported on axially aligned bolts rigidly mounted centrally of said heads, said bolts penetrating the branches of said magnet well above its center of mass whereby to create an unbalanced condition of weight between the magnet portions respectively above and below the axis of said bolts, the magnet portion above the axis being the lighter and comprising the poles which are disposed contiguous to the drum wall, and a rubber band interposed between the branches of said magnet with the ends of said band attached respectively to one of said bolts and to one of the magnet branches; said truck comprising a platform, a pin extending upwardly therefrom for supporting a toy member, and rollers of magnetic material revolvably supported from said platform and adapted for traction on the outer surface of said drum wall, said truck being movably held against the upper portion of the drum surface by magnetic attraction between said magnet and said rollers.

2. A roller toy comprising a drum, and a truck; said drum comprising a circularly formed wall of non-magnetic material, oppositely disposed heads, a substantially U-shaped magnet rotatably supported on axially aligned bolts penetrating the branches of said magnet, said bolts rigidly mounted centrally of said heads, the upper portions of the branches of said magnet constituting the poles which are inwardly directed toward each other and disposed contiguous to the inner surface of said drum wall, and a rubber band interposed between the branches of said magnet with the ends of said band attached respectively to one of said bolts and to one of the magnet branches; said truck comprising a plat-

form, a pin extending upwardly therefrom for supporting a toy member, and rollers of magnetic material revolvably supported from said platform and adapted for traction on the outer surface of said drum wall, said truck being movably held against the upper portion of the drum surface by magnetic attraction between said magnet and said rollers.

3. A roller toy comprising a drum, and a truck; said drum comprising a circularly formed wall of non-magnetic material, oppositely disposed heads, a substantially U-shaped magnet rotatably supported on axially aligned bolts penetrating the branches of said magnet, said bolts rigidly mounted centrally of said heads, the poles of said magnet being contiguous to the drum wall, the base portion of said magnet being thickened to provide weight whereby said magnet will normally and operatively be substantially in a vertical position, and a rubber band interposed between the branches of said magnet with the ends of said band attached respectively to one of said bolts and to one of the magnet branches; said truck comprising a platform, a pin extending upwardly therefrom for supporting a toy member, and rollers of magnetic material revolvably supported from said platform and adapted for traction on the outer surface of said drum wall, said truck being movably held against the upper portion of the drum surface by magnetic attraction between said magnet and said rollers.

4. A roller toy comprising a drum, and a truck; said drum comprising a circularly formed wall of non-magnetic material, oppositely disposed heads, a substantially U-shaped magnet rotatably supported on axially aligned bolts penetrating the branches of said magnet, said bolts rigidly mounted centrally of said heads, the upper portions of the branches of said magnet being inwardly directed toward each other and disposed contiguous to the inner surface of said drum wall, the base portion of said magnet being thickened to provide weight whereby said magnet will normally and operatively be substantially in a vertical position, and a rubber band interposed between the branches of said magnet with the ends of said band attached respectively to one of said bolts and to one of the magnet branches; said truck comprising a platform, a pin extending upwardly therefrom for supporting a toy member, and rollers of magnetic material revolvably supported from said platform and adapted for traction on the outer surface of said drum wall, said truck being movably held against the upper portion of the drum surface by magnetic attraction between said magnet and said rollers.
